UNITED STATES PATENT OFFICE.

LOUIS H. HOSBEIN, OF CHICAGO, ILLINOIS, ASSIGNOR TO M. H. DETRICK COMPANY, OF CHICAGO, ILLINOIS, A CORPORATION OF ILLINOIS.

FURNACE-ARCH CONSTRUCTION.

Application filed August 3, 1921. Serial No. 489,411.

To all whom it may concern:

Be it known that I, LOUIS H. HOSBEIN, a citizen of the United States, residing at Chicago, in the county of Cook and State of

5 Illinois, have invented certain new and useful Improvements in a Furnace-Arch Construction, of which the following is a specification.

10 This invention relates to the arches or crowns of boiler furnaces, and particularly to the types of such arches which are commonly known as suspended arches. The present invention resides primarily in a novel organization and arrangement of the parts constituting the arch itself with associated parts of the furnace and boiler structure. Other features of the invention reside in the novel construction of the arch itself and of the portions constituting the suspending means.

15 The general object of the invention is the provision of an improved and simplified construction for boiler furnaces whereby the provision of special supporting members for carrying the suspended arch is obviated, and installation and repair of the arch facilitated.

20 A more particular object of the invention is the provision of a novel furnace construction which obviates the necessity for the use of a special supporting member for the rear end of the arch, and which thereby saves space in the design of the furnace and material in its construction, which permits increase of the volume and the efficiency of the furnace and boiler by minimizing the vertical distance between the arch and the boiler tubes, and which permits the independent support of the several sections of the arch, facilitating the repair of an injured section without requiring the complete dismantling and reconstruction of the arch.

25 Another object of the invention is the provision of a suspended arch structure for boiler furnaces, which is designed for incorporation into boiler furnaces irrespective of whether they are originally designed and constructed for a suspended arch.

30 Another particular object of the invention is the provision of a suspended arch construction designed to be supported or suspended from the tubes of the boiler, and so arranged as to protect the suspending and

supporting portions, and to minimize possibility of injury to the arch incident to failure of any of the boiler tubes. 55

A further particular object of the invention is the provision of a novel suspended arch construction designed to be supported from the boiler tubes and adapted to be assembled with furnaces of different design and dimensions, and adapted to be constructed in various widths and lengths. 60

Another object of the invention is the provision of a furnace construction wherein a suspended arch is supported from the boiler tubes without imposing injurious stresses upon the latter incident to expansion or contraction of the arch. 65

Another object of the invention is the provision of an improved arch construction which will facilitate assembly of the structure and replacement of individual refractories, and which will make possible, in suspended arch construction, the use of refractories of relatively small size and having minimum surface area exposed in the furnace chamber. 70

Another object of the invention is the provision of such a construction particularly adapted for use in curved or convex portions of the arch. 80

A further object is the provision of such a construction which will contribute to diffusion of heat from metallic supporting 85 members, and thereby guard them against the deteriorating effects of high temperatures in the arch.

An incidental object of the invention is the provision of an arch structure having 90 the various characteristics above specified, which may be manufactured economically and installed quickly, due to the adaptability of a single design to a variety of situations, the extensive use of duplicate parts, and the 95 simplicity of the construction.

Other and further objects of the invention will be pointed out hereinafter, indicated in the appended claims, or obvious upon an understanding of the invention from 100 the present disclosure.

While the present application is predicated upon a disclosure of a preferred form and certain modified forms of construction, it is to be understood that the disclosure of 105 these particular embodiments of the inven-

tion is entirely for the purpose of illustration, and is not to be accorded any significance operating to limit the invention short of its true and most comprehensive scope in the art; as I am aware, and as will occur to others skilled in the art, that the invention is susceptible of embodiment in many other forms differing in particular respects from those herein shown.

10 In the accompanying drawings forming part of this specification,

Fig. 1 is a diagrammatic illustration in the nature of a part longitudinal sectional elevation of a furnace structure embodying 15 my invention;

Fig. 2 is a detail in the nature of a fragmentary sectional elevation taken on the line 2—2 of Fig. 1;

Fig. 3 is a similar detail showing a modified form;

Fig. 4 is a detail in the nature of a side elevation of a hanger of the sort shown in Fig. 2 showing an alternative modification in dotted lines;

Fig. 5 is a side elevation of a hanger bar;

Fig. 6 is an end elevation of the same;

Fig. 7 is a diagrammatic illustration of modified construction, same being in the nature of a part sectional elevation of the 30 arch, with tile suspension members shown in elevation;

Fig. 8 is a detail in the nature of an enlarged view of the rear end arch construction illustrated in Fig. 7; and

Fig. 9 is a detail in the nature of a fragmentary section substantially on line 9—9 of Fig. 7.

The construction constituting the subject matter of the present invention possesses 40 particular utility in furnace structures wherein the boiler is of the so-called horizontal water tube type. Described generally, one embodiment of the invention contemplates an arch structure constituting the 45 crown wall of the furnace, which arch is formed of a plurality of rows or series of firebrick or tile, the brick in each series being suspended on an arch bar extending longitudinally of the furnace, said respective arch bars being positioned so that the 50 tile of juxtaposed series are in contact. The forward extremities of these arch bars are supported upon or adjacent the front wall of the furnace, while at their rearward 55 extremities, under or adjacent the forward end of the boiler, the several arch bars are carried in a transversely extending hanger bar which, in turn, is suspended by a plurality of hangers which find support at their 60 upper extremities on tubes of the boiler. The invention will be understood more in detail by reference to the accompanying drawings, in which, in the embodiment illustrated in Fig. 1, the numeral 1 designates 65 the front wall of the furnace, with which

may be associated one or more transversely extending structural members 2, here illustrated in the form of a channel beam. The boiler front is designated by the numeral 4, behind which is set the front header 5 70 carrying the tubes 6, all supported in customary appropriate fashions. It is obvious that the width of the furnace and the depth of the furnace from the front wall to the forward end of the boiler will vary in different installations, and it is one of the features of utility of my invention that it is applicable to furnaces varying in these particulars by substitution or variation of only a minimum number of parts.

80 The arch itself includes a plurality of arch bars 7 extending from front to rear above the furnace chamber. In the embodiment illustrated in Fig. 1 each of these arch bars is formed as a composite structure comprising a front section and a rear section which are joined by a transverse key 8 passing through overlapping and interfitting parts of the connected sections. The bar has a hook-shaped forward extremity 9 supported upon and engaging over the structural member 2, whereby rearward movement of the bar is limited. The bar is provided throughout its length with a laterally projecting bottom flange 10 constituting a 90 tile retaining portion, and at its rearward extremity with a hook-like projection 11 constituting a tile support. For a distance adjacent its rear end, each bar is provided along its upper margin with a laterally extending suspension flange 12 which terminates at a stop member 14 disposed at the 100 rearward extremity of the bar. The several bars are conjointly supported at their rearward extremities on a hanger bar 15 extending transversely of them at substantially right angles. Supporting connection of the arch bars and hanger bar is afforded by slotted bracket members 16 adapted to receive the web of the arch bar between them 110 and to engage under the supporting flange 12. Abutment of the hanger bar against the stop 14 prevents its movement off of the rearward end of the arch bar. The bracket members 16 are supported by intermediate webs 16^a depending from the bottom flange 16^b, which, in turn, is connected to the top flange 16^c by a web 16^d. The hanger bar 15 is carried by a plurality of 115 hangers 17. Each of these hangers includes a shank portion terminating at its lower extremity in a jaw portion 17^a, and at its upper extremity in a laterally extending tube engaging portion 17^b. The jaw portion 120 is adapted to be slid onto the hanger bar, accommodating passage of the web 16^d and engaging under the top flange 16^c. The dimensions of the hanger shank and tube engaging portions are such as to permit the 125 upper portion of the hanger being inserted 120

- between juxtaposed tubes 6 of the boiler, and then rotated to engage the tube engaging portion 17^b over a boiler tube. In the embodiment illustrated in Fig. 2, the tube engaging portion is in the form of a hook which is adapted to find support upon a single boiler tube, while in the embodiment illustrated in Fig. 3 the tube engaging portion is adapted to find support upon two juxtaposed boiler tubes. The portions of the members 17^b adapted to have engagement with the boiler tubes are of arcuate cross contour so as to provide rocker bearing surfaces.
- 15 Each of the arch bars 7 affords a support for a plurality of tile 18 of refractory material, said tile being provided with marginal slots to receive the web and flange 10 of the bar, by virtue of which connection the tile of the series are held in proper alignment. The spacing of the brackets 16 on the hanger bar 15 is such that the tile on adjacent arch bars are supported in lateral contact. Tile maintained in this relationship constitute a continuous arch or crown sheets of heat resisting material.
- It is obvious that considerations of economy demand that the tile be manufactured in standard or established sizes, and that standard parts be utilized as extensively as possible in all installations. My invention contributes very materially to this desired result. Different transverse dimensions of furnaces may be accommodated by the use of more or fewer of the hanger bars 15, such as may be requisite to support the necessary number of series of tile; and proper support for the hanger bars is always afforded without special fittings, due to the fact that the hangers, whose position is dependent upon the position of the boiler tubes, are engageable with the hanger bar at any point throughout its length. Regardless of any change or variation in the spacing or position of the hangers, therefore, the tile are always suspended in proper relationship to form the continuous arch. It is obvious that for furnaces of different lengths, arch bars 7 of different lengths must be provided. In accommodating the structure to installations varying in this particular, the only variation necessary is in length of the front arch bar section. By utilization of front arch bar sections of proper length, and the requisite number of tile, the structure may be accommodated to any length of furnace, all the other parts being of standard sizes and construction. Variation in the elevation and angularity of the arch and the boiler tubes is accommodated by the arcuate bearing connection of the hangers and tubes, and by the extent of adjustment afforded as to the position of the hanger bar 15 upon the support flanges 12 of the arch bars.
- 65 It will be observed that by the use of the form of hanger shown in Fig. 2, the structure may be supported from the second series of boiler tubes, in distinction to being supported on the first or bottom series of tubes as shown in Fig. 3. It is found to be 70 of material advantage to support the arch from the second series of tubes rather than the first series, because, while tubes in the first row have to be replaced with comparative frequency, due to their burning out in 75 spots, replacement of tubes in the second row is seldom if ever necessitated from causes arising in the contemplated and customary use of the boiler.
- For the purpose of protecting closing the 80 front of the boiler setting and the metal parts of the arch structure and associated elements from the high heat of the furnace, an apron wall is included as a part of the arch construction. This apron wall includes 85 a transverse series of cover bricks 19, each supported upon one of the hook projections 11 of an arch bar, and of proper dimension to make lateral contact with juxtaposed similar bricks. These cover bricks cover 90 the ends of the arch bars and close the space between them, and they further support such additional bricks 20 as may be necessary to close the space between the cover bricks and the lowest series of boiler tubes, while asbestos packing 21 is utilized to fill the space about and between the lower tubes in front of the hangers 17.
- In the embodiment illustrated in Fig. 7 I have illustrated certain variations in the 100 construction. In many instances it is desirable to supply supports for the arch bars between the front wall and the boiler. In said figure I have shown such supports in the form of transversely extending channel 105 beams 22 supported at their ends in the side walls, and joined by the customary tie bolts 24 in cooperation with the spacers 25, and hangers 26 support the arch bars from these beams. Furthermore in this embodiment the 110 rear end of the arch is of variant type. The rear arch bar section is in arcuate form, and is attached to the bracket 16' by a bolt 27. The hanger bar 16 is carried in jaw members 28 which are clamped between hangers 29 115 under retention of bolts 30. On their opposite inner faces the hangers 29 are provided with seats, in which the upper flange of the jaw member 28 may be positioned selectively to obtain the desired elevation of the rear end of the arch. In this construction segmental tile are supported on the arcuate rear section of the arch bars, forming the curved or fan shaped apron wall. The construction of the arch at a point where it changes direction, particularly where the direction of the combustion gases change, is of great importance, as at such points the arch is subjected to the most intense heat, as well as the erosive action of the gases. The fan or turn 120 125 130

construction illustrated in Figs. 7, 8 and 9 constitutes a distinct improvement in arch construction designed to greatly increase the term of serviceability of the tile, as well as to facilitate installation and repair. It will be recognized that the material in the arch at such a turning point, as along the line of convergence of the horizontal and vertical wall portions, receives more heat than other parts of the arch, due to the passage past it of all combustion gases which are generated in the various points in front of it, and due to the fact that the material has faces exposed to the heat on two sides. Almost invariably it is this portion of the arch in which the refractory tile first have to be replaced. By my improved construction I minimize the destructive effect of the heat on the arch by making the turn very short, so as to minimize the amount of overhang at the point where the gases tend to change direction, provide an arrangement whereby it is possible to employ small size tile economically, and a supporting arrangement which is effective to increase radiation of heat from the tile and the arch bars. Moreover the arrangement permits the use of a minimum number of tile of minimum size, so that it is necessary to demount but very few tile in order to replace those which may become injured in the portion of the arch subject to most rapid disintegration. From the last mentioned figures it will be observed that the rear end arch bar section, here designated by the numeral 40, is quite short, and extends almost directly up from the end of the front section, being connected to the latter by the wedge 8 as in the form first described. The rearward margin of the section 40 is arcuate and throughout a portion of its length the bar has laterally extending arcuate flanges 41 following said margin. The segmental tile, while of sufficient thickness to permit the turn being made with a minimum number of tile, in the structure illustrated there being three of them, are only half the width of the tile employed in the horizontal portion of the arch. This arrangement permits the use of tile of such a small size as to increase their serviceability two or three times over the term of utility of a tile of the full width. In order to provide for the proper support of these half-width tile, as well as to afford an effective radiating means for conveying heat away from the tile and the arch bars, I employ supplemental suspension members 42. These supplemental suspension members are of a general anchor shape, and provided with transverse slots for reception of the webs and supporting flanges 10 and 41, of the arch bar members, so that said supplemental suspension members may be retained on the arch bars, while susceptible of movement longitudinally thereon. The supplemental suspension members have laterally

extending hook portions 42^a arranged to extend in substantially the plane of the retaining flanges 10 or 41 when the supplemental suspension member is positioned thereon. The supplemental suspension members also have upwardly extending arms 42^b which are relatively thin and of substantial width, and which are inclined obliquely so as to be spaced apart from the web of the arch bar when the supporting member is therein. These arms 42^b will be hereafter referred to as radiating fins. The half-width tile are formed with notched corners providing upstanding suspension lugs at their thinner extremities, to afford suspension pockets 33 adapted for reception of the hook members 42^a, said suspension lugs being shaped to conform to the position of the radiating fins 42^b, the form of the half tile being such that when two of them are suspended on one of the members 42 their juxtaposed faces contact and the two are of the same aggregate width as one of the full width tile. Therefore, when thus supported in conjunction with similar series of tile on adjacent arch bars, the arrangement presents a continuous wall of refractory material. It is obvious that the supplemental suspension members form anchors for retaining the half-width tile upon the arch bars, and in addition to this function, they constitute heat dispersing members which are effective to conduct heat from the tile and from the arch bars and, through the medium of the radiating fins 42^b, disperse this heat into the air above the arch by radiation. With the supplemental suspension members substantially enclosed by the tile, they would be subject to destructive overheating, but the provision of the radiating fins extending from the enclosed portions into the open air, is effective to avoid that contingency, in the manner just mentioned. The turn portion of an arch constructed in this fashion is adapted to resist the destructive influences of the heat to which it is subjected, due to the relatively small area of the individual tile exposed to the combustion gases. These various sections of the tile are susceptible of individual movement to a limited extent, as they are freely suspended, and being of relatively small cross sectional dimensions are more uniformly affected by changes in temperature, and thus are not so subject to disintegration as are the larger tile heretofore employed. Moreover the construction of the turn portion of the arch in this fashion permits the reduction in number of tile included in the vertical wall, and thereby greatly reduces the number of tile which it is necessary to dismount in order to replace tile at the bottom or median point of the turn, where the erosion and disintegration take place most rapidly. By the construction of the terminal arch bar member 40 with a shelf 130

44 for supporting the upper tiles of the apron wall, replacement of the lower tiles may be made without removal of the upper ones. It is obvious that any of various 5 forms of hangers or hanger bars may be employed with this rear end construction, and that a similar construction may be employed at the front end where it is desirable to provide an ignition arch between the front 10 wall and the horizontal arch.

In the assembling of arches comprising the features first above described, the hangers 15 are first placed in position on the proper water tubes and structural members, the hanger bars 15, of proper number to carry the necessary arch bars are then threaded into the jaw portions 17^a, the arch bars then mounted in the connection brackets, and the tile then hung upon the arch 20 bars.

A particular advantage gained by my invention is the conservation of head room, and facility of installation and repair effected by the elimination of the structural 25 supporting member heretofore employed at the rear end of furnace arches. In addition to requiring a very considerable vertical space, thus necessitating the lowering of the rear end of the arch relative to the 30 boiler, such transverse supporting members, being loaded over a considerable span, are subject to sagging when overheated. As they are utilized to carry the entire rear end of the arch, the replacement of such a member necessitates the complete dismantling 35 and rebuilding of the entire arch. By my improved construction, not only may any section of the arch be repaired without requiring dismantling of other parts, but the 40 failure of one support will not affect other than the immediate section of the arch. Moreover the rear end of the structure being supported at a plurality of points, on a plurality of different members, and at 45 points where such members are directly anchored and supported,—as are the boiler tubes in the head,—the supporting parts are further adapted to sustain the weight without strain. All metal parts of the structure 50 are effectively protected from excessive heat, and are quickly accessible by removal of a minimum number of tile. The construction permits the use of standard parts, with the sole exception of the rear arch bar sections, 55 in all installations, irrespective of the size of the arch, and the structure is adapted for incorporation into furnaces which are not designed particularly therefor.

I claim:

60 1. In a furnace construction, the combination with furnace walls and a boiler associated therewith, of arch bars supported at their forward portions and having their rearward extremities suspended from the boiler tubes, and refractory tile suspended

in series upon said arch bars to form a top for the fire chamber covering said arch bars and the connection to the boiler tubes.

2. In a boiler furnace including furnace walls and an associated boiler, a suspended arch including a plurality of longitudinally extending arch bars supported at their forward portions, a hanger bar affording a connecting support for said arch bars at their rearward extremities, separate hangers supported on tubes of the boiler and carrying said hanger bar, and tile suspended on the arch bars in association to constitute the furnace arch.

3. In a furnace construction including a furnace wall and an associated boiler, an arch structure comprising a series of longitudinally extending arch bars supported at their forward portions, a suspension member cooperating with said arch bars at their rearward extremities to maintain them in proper spacial relationship, individually adjustable hanger members connected to respective boiler tubes and conjointly supporting said suspension member, and tile suspended on the respective arch bars and cooperating to form a continuous arch between the furnace wall and the boiler.

4. In a furnace construction, the combination with a furnace wall and associated boiler, of an arch comprising a plurality of longitudinally extending arch bars formed of demountably conjoined sections, said arch bars being supported at their forward portions, a suspension member connecting the rear sections of the arch bars and effective to maintain them in proper spacial relationship in alignment respectively with their associated front sections, separate hangers suspended on respective tubes of the boiler and conjointly supporting the suspension member, and tile suspended on the several arch bars in association to afford a continuous top closure between the furnace wall and boiler.

5. In a boiler furnace an arch construction comprising longitudinally extending arch bars, a transversely extending suspension member connecting said arch bars adjacent their rear extremities, hangers supported on respective boiler tubes and constituting suspending means for said suspension member, said hangers having rocking bearing upon the boiler tubes.

6. In a boiler furnace including a tubular boiler, an arch construction comprising longitudinally extending arch bars, a plurality of hangers adapted for suspension individually upon respective boiler tubes and shiftable longitudinally on said tubes, a transversely extending suspension member insertable longitudinally into connection with said hangers, said arch bars being insertable longitudinally into connection with said suspension member to find support

- thereon at their rearward extremities, and tile suspended on the several arch bars and contacting to form a top closure extending below the forward end of the boiler.
- 5 7. In a boiler furnace including furnace walls and a water tube boiler, an arch construction comprising longitudinally extending arch bars arranged side by side and supported at their forward portions, a plurality 10 of hangers suspended individually on respective boiler tubes adjacent their connection with the header, supporting connections between the rear ends of the arch bars and said hangers, and tile suspended on the arch 15 bars in association to form a top closure wall between the furnace walls and boiler.
8. In a boiler furnace including furnace walls and an associated boiler, an arch construction comprising longitudinally extending arch bars supported at their forward 20 portions, a plurality of hangers supported severally on respective boiler tubes, connections between said hangers and the rearward ends of the arch bars to form a rear end 25 support for the latter, and tile suspended on said arch bars to form a top closure wall for the combustion chamber and an apron wall between said top closure wall and the boiler.
- 30 9. In a boiler furnace including furnace walls and an associated boiler, an arch construction comprising a plurality of arch bars having support at their forward portion and including upwardly extending portions 35 at their rearward extremities, a plurality of hangers supported individually on respective tubes of the boiler, connections between said hangers and the rear portions of said arch bars to constitute rear end 40 supports for the latter, and tile supported on said arch bars in association to constitute a suspended fire arch and apron wall.
10. In a boiler furnace including furnace walls and an associated boiler, an arch construction comprising a plurality of arch bars having support at their forward portions and having upwardly extending arcuate portions at their rearward extremities, hangers 45 individually supported on respective tubes of the boiler, connections between said hangers and arch bars to afford rear end support for the latter, and a plurality of tile suspended on the arch bars in association to 50 form a top closure for the combustion chamber and including an arcuate portion deflected upwardly toward the boiler.
- 55 11. In a boiler furnace including furnace walls and an associated boiler, an arch construction comprising a plurality of substantially 60 horizontally disposed front arch bar sections, a plurality of rear end arch bar sections having upwardly extending portions, a plurality of hangers supported individually on respective tubes of the boiler, connecting means joining said hangers and

rear end sections to afford support for the latter, means connecting the front and rear end arch bar sections, and tile suspended on said front and rear sections in association to constitute the furnace arch.

70

12. In a boiler furnace the combination with furnace walls and a water tube boiler of a plurality of arch bars, a plurality of hangers individually supported upon respective boiler tubes above the lowermost series 75 thereof, means affording supporting connection between said hangers and arch bars, and refractory material supported on said arch bars in position to form an arch segregating said arch bars and hangers from the 80 combustion chamber.

80

13. In a furnace an arch construction the combination of an arch bar formed with a supporting flange, means for supporting said arch bar, a plurality of supplemental 85 supporting members supported on said flange and susceptible of longitudinal movement thereon, and a plurality of tile supported on each of said supplemental supporting members, the tile on respective supplemental supporting members being associated to form a continuous furnace arch wall.

90

14. In a suspended arch construction the combination of arch bars having arcuate 95 supporting flanges, a plurality of supplemental supporting members retained on said flanges and susceptible of longitudinal movement thereon, and a plurality of tile supported on each of said supplemental supporting members, the tile on associated supplemental supporting members affording a continuous 100 arch wall having surface portions lying in different angular planes.

100

15. In a suspended arch, the combination of an arch bar having a supporting flange, a series of tile of substantially uniform width suspended on said flange, supplemental supporting members supported on the flange and longitudinally shiftable thereon, and a plurality of tile supported on each supplemental supporting member, the aggregate width of the tile on each supporting member substantially equalling the width of the tile on the supporting flange.

105

16. In a furnace arch, the combination of an arch bar having a supporting flange, a plurality of tile supported on said flange in alignment, a supplemental supporting member supported on said flange, and a plurality of tile supported on said supplemental supporting member in alignment with said first mentioned tile.

110

17. In an arch construction, the combination of an arch bar having a tile supporting portion, a plurality of tile suspended on said portion, a supplemental tile supporting member supported on said tile supporting portion, and a plurality of tile supported on said supplemental supporting member; said supplemental supporting member including 125

120

130

- heat radiating portions extending away from the tile and the arch bar.
18. In an arch construction, the combination of an arch bar having an angularly diverted part, said arch bar including said diverted part being provided with tile supporting portions, a plurality of supplemental supporting members supported on said tile support portion and the angularly diverted part, and a plurality of tile supported on each of said supplemental supporting members in association to form an arch wall portion, said supplemental supporting members including heat radiating portions projecting above said tile.
19. In a suspended arch, the combination of a plurality of arch bars having upwardly diverted portions at their rearward extremities, a plurality of rectangular tile of substantially equal width supported in a series on each arch bar, a plurality of wedge shaped tile supported on the diverted portion of each arch bar in lateral and longitudinal abutment, said wedge shaped tile being of substantially one-half the width of the rectangular tile and shiftable relative thereto on the arch bars, said rectangular tile being associated to constitute a substantially horizontal arch portion, and said wedge shaped tile being associated to constitute an arch portion in continuation of said horizontal portion but extending upwardly therefrom.
20. In an arch construction, the combination of an arch bar having an upwardly diverted rear end portion, said arch bar and said rear end portion having tile supporting members, a series of rectangular tile supported on said arch bar in alignment to form a flat arch and a plurality of series of wedge shaped tile supported on said rear end portion to form an arcuate continuation of said flat arch.
21. In furnace arch construction, the combination of an arch bar, tile adapted to be suspended thereon to form an arch portion, said tile having parts adapted to partially enclose the lower portion of the arch bar, tile hangers shiftable mounted on the arch bar for movement longitudinally thereof, said hangers having parts to engage the tile to support the latter on the bar and having parts extending clear of the tile to radiate heat.
22. In furnace arch construction, the combination of an arch bar, a plurality of tile hangers shiftable mounted thereon for movement longitudinally of the bar, tile having overhanging portions engageable on said hangers whereby the tile may be supported on the bar, and said hangers being provided with heat radiating portions extending outwardly from the tile between said overhanging portions thereof.
23. In furnace arch construction, the combination of an arch bar having a marginal flange, hangers shiftable mounted on said flange for movement longitudinally of the bar, tile mounted on said hangers with portions partly enclosing said flange, and said hangers being provided with parts projecting outwardly from the tile between said portions thereof.
24. In furnace arch construction, a tile hanger comprising a rigid member having a middle recess for reception of an arch bar, laterally projecting tile engaging members, and an arm extending upwardly between the tile engaging members adjacent the bar receiving recess.
25. In furnace arch construction, a tile hanger comprising a metallic member having laterally extending tile engaging portions, an upwardly extending arm intermediate said tile engaging portions and bar engaging parts intermediate the tile engaging portions, whereby the hanger may be shiftable mounted on a support.
26. In a boiler furnace construction including a water tube boiler, the combination of a plurality of arch bars having end portions adjacent the boiler, hangers sustained on the boiler tubes and supporting said end portions of the bars and refractory material supported on the bars in position to form the furnace arch.
27. In a furnace arch construction, in combination, an arch bar, hangers supported on respective bars and shiftable longitudinally thereon, a plurality of arch tile suspended on each hanger independently, said tile being shiftable with their supporting hangers and removable therefrom individually.
28. In a furnace arch construction, in combination, an arch bar, hangers mounted thereon and shiftable longitudinally of the bar, tile supported on said hangers and having portions pocketing a margin of the bar, said hangers having parts extending beyond the ends of the tile whereby the hangers may be engaged to shift them and the supported tile on the bar.
29. In furnace construction, the combination of a supporting bar, tile having slotted portions to receive a part of the bar, and hangers supported entirely by said bar and engaging the tile to support the latter upon the former.
30. In furnace construction, the combination of a bar, tile having recessed portions to accommodate the bar and hangers supported solely by said bar, said hangers being shiftable on the bar and engageable with the tile to support them thereon.
31. In arch construction, in combination, a supporting bar, tile having recessed portions to accommodate portions of the bar,

and hangers supported entirely by said bar and extending laterally therefrom for engagement with the tile to support them on the bar, there being a plurality of tile on each hanger.

32. In arch construction, in combination, a bar having a marginal flange, tile having recessed portions to accommodate the flange, and hangers adjustably supported on the flange for engagement with the tile.

33. In furnace construction, the combination with a supporting bar, of hangers removably supported solely by said bar and projecting laterally to opposite sides thereof, and tile suspended on the hangers and pocketing portions of the bar, said hangers being shiftable on the bar to accommodate movement of the tile to different elevations thereon.

34. As an article of manufacture a furnace arch portion comprising identical wedge shaped refractories provided at one side of their narrower ends with a notched corner portion and hook receiving pocket extending inwardly therefrom and terminating short of the converging faces of the refractories, and the lateral faces of the refractories being parallel.

35. An arch construction comprising the combination with the top arch, of supporting brackets arranged along a margin thereof, suspension members movably supported on the brackets at different elevations, and wedge-shaped tile suspended on the suspension members in courses terminating at the margin of the top arch, the tile in the respective courses being disposed edge-to-edge and

the movable suspension members accommodating their expansion and contraction.

36. As an article of manufacture, an arch nose portion comprising complementary wedge-shaped refractories having parallel lateral sides and notched inner corner portions at their narrower ends, said narrower end portions being provided with hook-receiving pockets disposed to align when the refractories are arranged with lateral faces in abutment and the converging faces in approximate alignment.

37. An arch nose construction comprising a vertically extending supporting bracket, tile supporting members adjustably supported thereon at different elevations, wedge-shaped tile suspended on said supporting members and shiftable therewith relative to the bracket, said wedge-shaped tile being disposed with their convergent faces juxtaposed and their narrower extremities in engagement with the supporting members.

38. In a construction of the character stated a longitudinally disposed arch bar the lower portion of which is formed upon an arc of a circle, means for supporting said arch bar, laterally extended flanges upon the lower part of said arch bar also formed upon an arc of a circle, tiles arranged end to end and supported by said arch bar and tile hangers for engaging said tiles and said flanges.

In testimony whereof I have hereunto signed my name.

LOUIS H. HOSBEIN.

DISCLAIMER

1,544,580.—*Louis H. Hosbein*, Chicago, Ill. FURNACE-ARCH CONSTRUCTION. Patent dated July 7, 1925. Disclaimer filed November 1, 1935, by the assignee, *M. H. Detrick Company*.

Hereby enters this disclaimer to that part of the claim in said specification which is in the following words to-wit:

“13. In a furnace an arch construction the combination of an arch bar formed with a supporting flange, means for supporting said arch bar, a plurality of supplemental supporting members supported on said flange and susceptible of longitudinal movement thereon, and a plurality of tile supported on each of said supplemental supporting members, the tile on respective supporting members being associated to form a continuous furnace arch wall.”

“34. As an article of manufacture a furnace arch portion comprising identical wedge shaped refractories provided at one side of their narrower ends with a notched corner portion and hook receiving pocket extending inwardly therefrom and terminating short of the converging faces of the refractories, and the lateral faces of the refractories being parallel.

“35. An arch construction comprising the combination with the top arch, of supporting brackets arranged along a margin thereof, suspension members movably supported on the brackets at different elevations, and wedge-shaped tile suspended on the suspension members in courses terminating at the margin of the top arch, the tile in the respective courses being disposed edge-to-edge and the movable suspension members accommodating their expansion and contraction.

“36. As an article of manufacture, an arch nose portion comprising complementary wedge-shaped refractories having parallel lateral sides and notched inner corner portions at their narrower ends, said narrower end portions being provided with hook-receiving pockets disposed to align when the refractories are arranged with lateral faces in abutment and the converging faces in approximate alignment.

“37. An arch nose construction comprising a vertically extending supporting bracket, tile supporting members adjustably supported thereon at different elevations, wedge-shaped tile suspended on said supporting members and shiftable therewith relative to the bracket, said wedge-shaped tile being disposed with their convergent faces juxtaposed and their narrower extremities in engagement with the supporting members.”
